UNITED STATES PATENT OFFICE.

JAMES DONALDSON, OF LAKE, ASSIGNOR OF ONE-HALF TO HENRY NOCK,
OF BAY VIEW, WISCONSIN.

INCUBATOR.

SPECIFICATION forming part of Letters Patent No. 248,295, dated October 18, 1881.

Application filed March 23, 1881. (No model.)

To all whom it may concern:

Be it known that I, JAMES DONALDSON, a citizen of the United States, residing at the town of Lake, county of Milwaukee, in the State 5 of Wisconsin, have invented certain new and useful Improvements in Incubators and Brooders; and I do hereby declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 My invention relates to improvements in a combined incubator and brooder; and it consists in an apparatus for hatching the eggs in an artificially-heated nest or inclosure and an open platform, so arranged that the brood have 20 free access to and from the platform to the nest.

My invention is further explained by reference to the accompanying drawings, in which—

Figure 1 represents a perspective view. Fig. 2 is a vertical section of the same. Fig. 3 represents a section of the egg-drawer.

Like parts are represented by the same reference-letters throughout the several views.

A represents the exterior walls of the hatching apparatus. B is the interior wall. The 30 space between these walls is filled with a packing, C, of charcoal, which surrounds the interior wall upon all sides.

D is the egg-drawer, which is supported upon cleats d d, and provided with a glass window, 35 B', through which the indications of a thermometer may be observed within the drawer while closed and the eggs inspected. Handles b b are for withdrawing the drawer. The bottom of the drawer is formed of sheet metal, 40 zinc being preferred, which is provided with small perforations d', and is covered with felt or other soft fabric, E, upon which the eggs to be hatched are placed.

F F are cold-water tanks, the office of which 45 is to supply the required moisture.

G and H are ventilating-tubes, which communicate from the central part of the incubator to the exterior air.

Heretofore it has been common to supply the 50 required heat from lamps, stoves, &c., which

are placed in direct contact with the incubator. By my improvement the required temperature is attained by filling a tank or reservoir from time to time with hot water which has previously been heated apart from the incubator, an 55 ordinary stove and tea-kettle serving well for the purpose.

I represents the reservoir, which is divided into two compartments, J and K. The reservoir being first filled, the required moderate 60 temperature is maintained by drawing off from time to time a small quantity of the cooled water and replacing the same with hot water. That the eggs be not destroyed by too great heat, the hot water is first admitted to the upper compartment of the reservoir, to which it is conducted by the funnel L, the cooler water being first withdrawn through the faucet M. The water thus introduced to the upper compartment mingles with the cooler water, and 65 is thereby reduced to the desired temperature before entering the lower compartment of the reservoir, into which it passes through the passage x as the water from below is drawn off through the faucet. The charcoal packing 70 serves to purify the incubator and retain the heat. Water is added from time to time, as mentioned, until the eggs are hatched, when the brood is moved from the drawer and placed in the nest or brooder N, which is located 75 directly above the hot-water reservoir I, and is kept warm by the heat which escapes from the water therein.

The brooder N consists in the inclosure formed by the cloth curtains P P P P, which 80 are suspended at the respective corners from posts R R R R. The bottom is formed of cloth or felt W, which rests upon the charcoal, through which the heat from the reservoir readily passes. The whole is provided with a closely-fitting 85 cover, O, (represented by dotted lines.) A broad open platform, S, surrounds the nest or brooder, upon which the chickens are at liberty to go at will by passing beneath the cloth P, as indicated. The margin of the platform is provided with a low lattice fence or railing, T, by 90 which the chickens are prevented from escaping therefrom. It is obvious that by this arrangement the chickens may be fed and exposed to the sun upon the platform when de- 95 100

sired, while they can find shelter from cold, without the aid of an attendant, within the brooder N, while the heated water in the reservoir I serves the twofold purpose of providing 5 heat for one brood while it is hatching another.

Heretofore it has been common to apply the heated water beneath the eggs, in which case it dissipates the required moisture. The eggs are more liable to become too hot, and a large 10 percentage of them become spoiled, while I have found by numerous experiments that a much larger percentage of the eggs are hatched when the heated water is introduced above the eggs and the required moisture is supplied 15 from below.

Having thus described my invention, what I claim as new, and desire to secure by Letters Patent, is—

The combination, with the herein-described incubator, of brooding-nest N, having close 20 cover O and flexible sides P, platform S, and railing T, all substantially as and for the purpose specified.

In testimony whereof I affix my signature in presence of two witnesses.

JAMES DONALDSON.
